CLAIM

The ornamental design for a mastic gun, as shown and described.

DESCRIPTION

FIG. 1 is a front perspective view showing one side of a mastic gun illustrating my new design:

FIG. 2 is a side elevation thereof;

FIG. 3 is a rear view thereof; and

FIG. 4 is an enlarged, fragmentary perspective view thereof with the trigger partially retracted.

FIG.1.

FIG.2.

FIG. 3.

FIG. 4.
